UNITED STATES PATENT OFFICE.

FRANCOIS X. DE BEUKELAER, OF ANTWERP, BELGIUM.

DESIGN FOR A BOTTLE.

No. 39,117.

Specification for Design.

Patented Feb. 11, 1908.

Application filed October 18, 1907. Serial No. 398,133. Term of patent 14 years.

To all whom it may concern:

Be it known that I, FRANCOIS X. DE BEUKELAER, a subject of the King of Belgium, and resident of Antwerp, Belgium, have invented a new, original and ornamental Design for Bottles, of which the following is a specification, reference being had to the accompanying drawing, forming part thereof.

The figure of this drawing is a front elevation showing design of the bottle.

I claim:
The ornamental design for a bottle as shown.

FRANCOIS X. DE BEUKELAER.

Witnesses:

G. DE LERSY,
A. ADAMS.
